GARMENT FOLDING MACHINE

Harry G. Cooper, West Medford, Mass., assignor
to The Prosperity Company, Inc., Syracuse,
N. Y., a corporation of New York

Application March 3, 1942, Serial No. 433,223

11 Claims. (Cl. 233—37)

This invention relates to garment folding machines, and more particularly machines for folding finished laundered garments, as shirts and the like, and has for its object a folding machine of this type, which is particularly simple in construction, fast in operation, and requires minimum effort on the part of the operator. It further has for its object a folding machine in which at least a part of the folding mechanism is power operated and the return of the folding mechanism to starting position controlled by the manual movement of a form, about which the garment has been folded by the folding mechanism, out of position over the table on which the garment is initially laid for folding.

It further has for its object a garment folding machine including at least sets of consecutively operable folding members, the first operating set being normally in position to fold the garment after it is laid on the table, and the second set being brought into operative position relatively to the garment by the movement of the form into a position over the garment and the table.

It further has for its object a control for the power actuation of at least a portion of the folding mechanism by two controls, one controlled by operator-operated means to effect the operation of the folding mechanism, and the other by the initial movement of the form away from the table to effect the return of all operating parts to starting position.

It further has for its object features of the actuating and control mechanism hereinafter described and claimed.

The invention consists in the novel features and in the combinations and constructions hereinafter set forth and claimed.

In describing this invention, reference is had to the accompanying drawings in which like characters designate corresponding parts in all the views.

Figure 1 is an isometric view of a garment folding machine embodying this invention.

Figure 2 is a fragmentary side elevation, partly in section, of parts seen in Figure 1.

Figure 3 is an enlarged, fragmentary plan view looking downwardly in Figures 1 and 2, illustrating the folding mechanism.

Figure 4 is an elevation looking upwardly in Figure 3.

Figure 5 is an enlarged detail view, partly in section, of one of the folding members and the means for holding it in folded position, this being a view taken approximately on the plane of line 5—5, Figure 3.

Figure 6 is a diagrammatic view of the actuating mechanism and the power system and controls therefor.

Figures 7, 8, 9 and 10 are operation views illustrating the consecutive folding operations.

Figure 11 (sheet 2) is a sectional view on the plane of line 11—11, Figure 5.

Figure 12 (sheet 1) is a fragmentary isometric view of the pivotal mounting for the frame of the form about which the garment is to be folded and its carrier, one set of folders, the form and other parts being in starting position.

Figure 13 (sheet 2) is a view similar to Figure 12 showing the position of the shaft of one set 15 of folders relative to the frame of the form at the end of the folding operation.

This machine includes, generally, a table on which the garment, as a shirt, is arranged or laid, a form mounted relatively to the table to shift 20 into and out of a position flatwise over the table, so that the garment may be folded around the form, power operated folding mechanism operable to fold portions of the garment relatively to other portions and the form, motor means for 25 operating the folding mechanism and a control for the motor means.

1 designates the table or the table top which is supported by an underframing 2 in any suitable manner. The table is formed with a recess 30 3 in the top thereof toward one end for receiving the collar C or neckband of a shirt or garment G when laid with the front down. Means is provided in this type of folding machine for coacting with the neckband or collar when in the recess 35 to hold the same or to hold and iron during folding operation. The collar and neckband holding or ironing mechanism forms no part of this invention.

4 designates the form, this being rectangular 40 in general outline with the center toward one end removed or notched for permitting the folded garment to be taken hold of and pulled or slipped off the form.

The form is shaped to hold a rectangular card- 45 board 5 which remains in the folded garment, when it is removed from the form. The cardboard instead of being placed on the form may be placed by the operator on the garment prior to bringing the form down on the garment. The 50 form is carried by a frame 6 pivoted or having bearings at 7 on a shaft 8 extending crosswise of a support or leaf 9 hinged at 10 to brackets 10^a at one end of the table (Figures 1 and 2). A spring 6^a normally holds the support 9 level with 55 the table top.

The folding mechanism comprises two sets of folding members. 11 designates one set of right and left folding members, and 12 the other set of right and left folding members. The shirt or garment, when initially laid by the operator on the table with the neckband or collar in the recess 3 (or with the front of the garment facing down) is also arranged so that the sleeves of the garment hang down from opposite edges of the table. The folding members 11 are initially arranged so that they are in juxtaposition to fold, when operated, the hanging sleeves up over the body of the shirt or garment and over the form 4 into the position shown in Figure 7. Each of the folding members 11 is in the general form of a crank including a crank shaft 13 and a crank pin 14 in the form of an arm or rod which coacts with the sleeve of the shirt or garment. There are suitable motion transmitting means between the motor of the actuating means and these cranks. The folding members 11 or the crank shafts thereof are mounted on the support 9 in suitable bearings 15. The motion transmitting means between the motor and these cranks, in the illustrated embodiment of the invention, consist of the shaft 8 which is mounted in suitable bearings 17 on the support 9 and connected at its opposite ends to the crank shafts of the folding members 11, as for example, through beveled gears 18, 19. This shaft 8 is connected to the motor, as will be hereinafter described.

The folding members 12 are carried by the frame 6 and are in the general form of cranks including a hub 20 mounted on a crank or rock shaft 21 (Figure 5) journaled in a bearing 22 carried by the frame 6 of the form 4. The portions of this crank formation, which coact with the garment to fold the same, normally extend in the plane of the form 4 and are shiftable bodily with the form into and out of a position flatwise over the table.

The actuating means includes a motor, and preferably a pressure-operated motor and a power and control system therefor. The motor is carried by the support 9 and partakes of the pivotal or tilting movement thereof. It is here shown as of the cylinder and piston type and comprises a cylinder 23 and a piston 24 working therein, the piston rod 25 of which is connected to the shaft 8 to rotate said shaft through suitable mechanism, as a rack and pinion. In the illustrated embodiment of the invention, the piston rod is formed with a rack 26 meshing with a pinion 27 mounted on the shaft 8 between the ends thereof. The piston rod 25 is also provided with a piston 28 at the end thereof remote from the piston 24, the piston 28 working in a cylinder 29 aligned with the cylinder 23. The pressure face of the piston 28 is less than that of the piston 24, and the cylinder 29 is connected to a source of motive fluid, as compressed air, which is in constant communication therewith, so that the piston 28 acts to return the folding mechanism to its starting position, when the pressure is released from the cylinder 23. The flow of motive fluid or compressed air to the cylinder 23 is controlled, as will be hereinafter described.

The frame 6 for the form is connected to the shaft 8 through a lost-motion coupling, which, during the power operation of the shaft 8 by the motor, also moves the form 4 about the axis of the shaft 8 into a position on the garment on the table 1 and which also permits continued movement of the shaft 8 to operate the folding members 11, after the form 4 is in a position

flatwise on the garment on the table 1. As here shown, this coupling consists of a rock arm 30, best seen in Figures 12 and 13, on the shaft 8 and having a transverse arm or pin 31 coacting with the frame 6, it coacting with a nose 32 extending to the opposite side of the axis of the frame 6 or shaft 8 from that on which the form 4 is located, when the form 4 and its frame 6 is in its starting elevated position (Figure 1). 10 When the shaft 8 is actuated and rotates clockwise, said arm 31 moves away from the nose 32, permitting the form to move by gravity flatwise down onto the garment on the table 1. As the form moves through an arc of less than 45°, 15 the arm 31 moves away from the nose 32 as the form 4 moves by gravity toward and into the position flatwise over the garment on the table 1 into the position shown in Figure 13. The shaft 8 during rotation thereof is actuating the folding members 11.

The folding members 12 are, in this embodiment of the invention, operated by hand, and one in advance of the other, the operation being against the action of returning springs 34, these being shown as torsion springs encircling the shafts 21, and each anchored at its opposite ends to a head on the shaft and to the bearing 22 (Figure 5). Releasable means are provided for holding the members 12 in their operated position, that is, the position shown in Figure 3.

In the illustrated embodiment of our invention, the holding means is power operated and released when the power is released. The holding means here shown frictionally holds the members 12 against return movement by the springs 34. The friction means illustrated consists of brake shoes 35, best seen in Figures 5, 6 and 11, coacting with a drum or hub 36 on the shaft 21 and each operated by a pressure-operated member, as a diaphragm 37 in a diaphragm chamber 38, the pressure side of which is connected to a source of supply of compressed air, as will hereinafter be described in connection with the power system. The diaphragm 37 thrusts against a plunger 39 which in turn thrusts against the brake shoe 35.

The power system includes a main supply line 41 having an open branch conduit 42 leading to the intake end of the cylinder 29 and a conduit 43 communicating with the intake end of the casing of a control valve 44 of the combined intake and exhaust type, this valve including a movable valve member having a normally closed intake valve head 45 and a normally open exhaust valve head 46, this valve being acted upon by a spring 47, which holds it in its normal position. In Figure 6, the valve is shown as in its operated position.

The power system also includes a conduit 48 leading from the casing of the valve 44 through a timer device 49 and conduit 50 to the intake end of the cylinder 23 and also from the timer device 49 through conduits 51 and 52 to the diaphragm chambers 38 respectively. The movable valve member of the valve 44 is operated from its normal position into the position shown in Figure 6 by an operator-operated member 53, which is connected by a rod 54 to an arm of a three-arm rocking lever 55, one arm of which coacts with the stem 56 of the movable member of the valve 44. This lever 55, and hence the movable valve member, is held in its operated position shown in Figure 6, by a pressure-operated device, as a diaphragm 57 in a chamber 58, the pressure side of which is connected by a duct 59 to the interior

of the valve casing 44. The diaphragm 57 acts through a plunger or stem 60 on another arm of the three-arm lever 55. Thus, when the operating member 53 is operated, and the exhaust valve head 46 closed and the intake valve head 45 opened, the air in its passage through the casing of the valve 44 into the pipe 48, also passes into the diaphragm chamber 58 through the duct 59 and holds the valve in its operated position. The operating member 53 is here shown as a lever pivoted at 61 between its ends to the under side of the table 1, and as having a head 62 extending beyond one side edge of the table and located to be pressed against by the body or the hip of the operator. This operating head 62 is so located that when the operator operates it, her hands are out of the range of movement of the folding members 11.

Means is provided for releasing the air from the cylinder 23 at the end of the folding operation, this including a release control operable by lifting of the form 4 with the shirt thereon to withdraw the folded shirt or garment therefrom. The release control member here shown is a normally closed exhaust valve for the diaphragm chamber 58. 63 designates the casing of the exhaust valve and 64 a normally closed exhaust valve head, which is pressed to closed position by a spring 65.

The exhaust valve casing 63 is connected by a pipe 66 to the pressure side of the diaphragm chamber 58. The valve head 64 has a stem 67. This exhaust valve is mounted on the table frame in position to be engaged by an arm 68 on the support or leaf 9 when the support is tilted, as will be presently described. The arm 68 has a yieldingly mounted head 69 for pressing against the stem 67 of the exhaust valve. Thus, the exhaust valve 64 is normally closed under the influence of its spring 65 or is in the position shown in Figure 6, so that upon operation of the operating lever 53, the air will flow to the cylinder 23, actuate the piston 24 therein, and also flow to the diaphragm chambers 38, and upon lifting of the form into the position shown in Figure 2, the exhaust valve head 64 will be opened, permitting air to exhaust from the diaphragm chamber 58, and hence the control valve in the casing 44 to return to its normal position, wherein the exhaust valve head 46 is opened and the intake valve head 45 closed. Upon this operation, the air can exhaust back through the pipes 50, 51 and 52, through the timer, as will be presently described, to the outer air, and also through pipe 48 and throttle therein and exhaust passage of valve casing 44, permitting the springs 34 to re-act and return the folding members 12 to their normal position and the piston 28 to re-act and return through the rack 26, pinion 27 and shaft 8, the folding members 11 to their starting position. The release of air from the diaphragm chambers 38 effects the release of the brake shoes 35 so that the spring 6^a returns the leaf or support 9 and frame 6 to its normal position (Figure 1) from that shown in Figure 2. When the brake shoes 35 are applied and the form 4 lifted to the angle shown in Figure 2, for the purpose of removing the folded garment therefrom, the form 4 is locked from pivotal movement about the shaft 8. Hence, when the upward tilting force is applied to the form, the frame 6 thrusts against the shoulder 31 (Figure 13) of the rock arm 30 (Figure 13), and as the form 4 can not pivot about the shaft 8, the support or leaf 9 is tilted about the pivot 10 (Figure 2) and the arm 68 actuated to open the exhaust valve head 64. This effects

the exhaust of air from the diaphragm chambers 38 and 58, and hence the release of the brake shoes 35 and the exhaust of the cylinder 23 and the actuation of the piston 28 and the cylinder 29, so that the spring 6^a is free to re-act to return the support or leaf 9 to the position shown in Figure 1. Also, under the action of the piston 28, the shaft 8 is actuated in a retrograde direction to return the folders 11 to starting position. This operation causes the shoulder 31 of the rock arm 30 to move from the position shown in Figure 13 to that shown in Figure 12, and during the latter part of this movement, when it moves into engagement with the nose 32, tilts the form 4 and its frame 6 into the position shown in Figure 1. The elevating movement of the frame is limited by a stop S. When the garment has been first laid on the table 1 and the control member 53 actuated, the shaft 8 is turned, permitting the form to drop by gravity from its elevated position flatwise on the garment on the table. The form reaches its position flatwise on the table when the shoulder 31 has completed about one-third of its movement from the position shown in Figure 12 to that shown in Figure 13.

The timer (Figure 6) includes the cylinder 49 and a piston 70 therein, the piston rod 71 of which is provided with a cross-head 72 to which returning springs 73 are connected. The cylinder is provided with ports arranged to be uncovered by the piston progressively, these ports designated A, B and C communicating respectively with the pipe 50 leading to the main cylinder 23 and to the diaphragm chambers 38^b, 38^c respectively, which operate brake shoes 35. The operation of the timer is of more consequence during the retrograde movement of the timer piston, in order to time the releasing of the brake shoes 35 consecutively or one ahead of the other, in order to prevent either from obstructing the other during the return of the folders 12 to their starting position.

In addition to the timer cylinder and piston 49, 70, the timing means includes a throttle valve in the pipe 50 for preventing too quick operation of the folding members 11 before the form 4 has been brought down flatwise on the garment to be folded. The timing means also includes an additional throttle valve in the pipe 48 to permit only sufficient movement of the piston 70 of the timer to uncover the ports C and B respectively consecutively on retrograde movement of the piston 70, or to prevent a too quick exhaust back through the pipe 48 and valve 44, when the exhaust valve 60 is opened by the lifting of the form 4 with the folded shirt thereon into the position shown in Figure 2. 48^a designates the throttle valve in the feed pipe 48 to the cylinder of the timer. 50^a designates a throttle valve in the pipe 50 leading from the port A in the timer to the cylinder 23. These throttle valves are check valves with bleeder passages or needle valve controlled passages therein. The throttle valve 48^a is reversely arranged from valve 50^a and is so arranged that the full pressure flows only into the timer cylinder 49 to actuate the piston 70 therein, when the valve 44 is operated to open the air intake head 45 and close the exhaust valve head 46 or valve 50^a is connected to the port A to be first uncovered and is arranged to throttle or cause the air to flow slowly from the timer cylinder through the pipe 50 to the cylinder 23 to the motor and to exhaust back freely. One construction of the throttle valve is illustrated in Figure 6, wherein the throttle valve 50^a is shown in section. The

throttle valve 48^a is of the same construction, except that it is reversely arranged with respect to the flow of power. Each throttle valve includes a spring-pressed check valve 500 and a by-pass or bleeder passage controlled by a needle valve 501 around the port controlled by the check valve.

The timer cylinder 49 is provided with exhaust ports 49^a at the outer end thereof. The pipe 51 to the diaphragm chamber 38^b leads from the port B of the timer cylinder; the pipe 52 to the other diaphragm chamber 38^c leads from the port C in the timer cylinder. The pipe 50 to the cylinder 23 of the motor leads from the first port A to be uncovered. Thus, upon the operation of the valve 44 to open its intake head 45 and close its exhaust head 46, air will flow from the main line 43 through the pipe 48 and throttle valve 48^a therein to the timer cylinder 49, actuating the piston 70 therein, so that the air first passes through the pipe 50 and throttle valve 50^a to the cylinder 23. As before stated, the throttle valve 48^a is so arranged as to open the pipe 48 to the full flow of power, and the throttle valve 50^a is arranged to throttle the air in its passage to the cylinder 23. Thus, when the piston 70 uncovers the port A, the piston 24 is actuated comparatively slowly giving time for the form 4 to come flatwise down onto the garment before the folders 11 have traveled far enough to complete the folding of the sleeves of the garment. This movement of the form 4 flatwise onto the garment also carries the folders 12 into position to fold before the folders 11 have folded the sleeves of the garment over onto the form, and the folders 12. When the piston 70 of the timer uncovers the ports B and C consecutively, and applies the brake shoes 35 consecutively, but during folding operation, this consecutive operation is of no consequence, but the consecutive releasing of these brake shoes is of consequence during the return of the parts from folded to starting position. Upon the uncovering of the port A, the form 4 first moves from the position shown in Figure 1, carrying the folders 12 therewith, and then the folders 11 complete the folding of the garment into the position shown in Figure 7. The operator then folds the folders 12 by hand, one after the other, as shown in Figure 8, into the position shown in Figure 9. She then folds the tail portion of the shirt from the position shown in Figure 9 to that shown in Figure 10; applies a retaining band R, and then lifts the form with the shirt thereon into the position shown in Figure 2, and slips the folded shirt off the form. The elevating of the form 4 with the shirt thereon into the position shown in Figure 2 opens the exhaust valve 64, as previously described, thus causing the control valve 54 to return to its normal position, wherein the exhaust valve head 46 is open and the exhaust valve head 45 closed, permitting the air to exhaust solely with a throttling action through the pipe 48 and the check or throttle valve 48^a therein. However, the throttling through the throttle valve 48^a is not sufficient to release the pressure in the cylinder 23 and the diaphragm chambers 38^b, 38^c, but is only sufficient to permit retrograde movement of the piston 70 under the action of the spring 73 sufficiently to uncover the ports C, B consecutively effecting the release of the brake shoes 35 consecutively so that the folding members 12 move out of their folded position consecutively and do not interfere with each other during their unfolding action. When the piston 70 uncovers

the ports C, B on its retrograde action, the air exhausts from the pipes 52, 51 behind the piston 70 through the ports 49^a to the outer air. When the piston on its retrograde movement uncovers the port A, the cylinder 23 is then freed of the slow throttling exhaust action of the throttle valve 48^a and can exhaust fully through the valve 50^a into the timer cylinder behind the piston 70 and out through the ports 49^a. The operator in folding the folders 12 by hand applies enough force to overcome the holding friction of the brake shoes 35.

In the general operation, the operator arranges the shirt on the table in the position shown in Figure 1, the cardboard 5 having been placed on the form 4 or on the garment. She then operates the operating member 53, which opens the valve intake head 45 of the control valve and closes the exhaust valve head 46 and the air flowing through the pipe 48 into the timer cylinder 49, actuates the piston 70 of the timer. The air then flows to the cylinder 23 and diaphragm chambers 38^b, 38^c as described, the form 4 dropping by gravity flatwise on the garment during the initial part of the movement of the folders 11. The flow of air to the cylinder 23 is timed by the throttle valve 50^a. The operator then immediately folds the left and right folding members 12 by hand into the position shown in Figures 2 and 3. She then makes any smoothing operations necessary and folds the tail portion of the shirt from the position shown in Figure 9 to that shown in Figure 10.

The band R is then applied. These holding bands R are arranged in a recess 74 in the table. The operator takes hold of the ends of one of these bands and brings the ends up around over the shirt and fastens them together by a pin, clip or adhesive. The operator then tilts the form 4 upwardly away from the table toward the position shown in Figure 2, and while doing so, slips the folded shirt and the cardboard therein, off the form. This operation of tilting the form also tilts the support or leaf 9 about the pivot 10 into the position shown in Figure 2, opens the exhaust valve 64 permitting the control valve heads 45, 46 to return to normal position with the intake head 45 closed and the exhaust head open, so that the parts return to their starting position ready for the next folding operation, the same being controlled or timed during the return by the timer means including the cylinder 49 and piston 70 and the throttle valves 48^a and 50^a.

What I claim is:

1. A garment folding machine including a table on which the garment is laid, a form pivotally mounted to shift into and out of a position flatwise over the table and the garment thereon, folding mechanism operable to fold portions of the garment relatively to the form and to other portions of the garment, power mechanism for operating the folding mechanism including means for permitting the operation of the form into a position flatwise over the table and the garment in advance of the folding of the garment about the form by the folding mechanism, an operator-operated control for effecting the operation of the power mechanism, and means operated by the movement of the form out of a position flatwise over the table to effect the unfolding of the folding mechanism and the return of the form to starting position.

2. A garment folding machine including a table on which the garment is laid flat, a form mounted to shift into and out of a position flat-

wise over the table and the garment thereon, folding mechanism including two sets of folding members, power mechanism for operating one set of folding members, the other set being independently operated; power mechanism for operating the first set of folding members and including means for permitting the operation of the form in advance of the folding operation by the first set of folding members about the form, and an operator-operated control for the power means, the independently operated set of control members being shiftable with the form into and out of position to operate to fold the garment.

3. A garment folding machine including a table on which the garment is laid flat, a form mounted to shift into and out of a position flatwise over the table and the garment thereon, folding mechanism including two sets of folding members, power mechanism for operating one set of folding members, the second set being independently operated, means for returning the latter set to starting position, means for holding the second set in operated position, power mechanism for operating the one set of folding members and including means for permitting the operation of the form in advance of the folding operation of the first set of folding members about the form, an operator-operated control for the power means, and means operated by the shifting of the form away from a position flatwise on the table, to control the operation of the power means to restore the power-operated folding members and the form to starting position, and release the holding means for the second set.

4. A garment folding machine including a table on which the garment is laid flatwise, a form mounted to shift into and out of a position flatwise over the table and the garment thereon, a motor, folding members operable to fold portions of the garment relatively to the form and to other portions of the garment, motion transmitting means between the motor and the folding members and the form, a power system for the motor including an operator-operated control operable to control the flow of power to the motor, and a second control member operable by the initial lifting movement of the form with the folded garment thereon from a position flatwise on the table to effect de-energization of the motor, and means for returning the folding mechanism and the form to their starting positions when the motor is de-energized.

5. A garment folding machine including a table on which the garment is laid flatwise, a form mounted to shift into and out of a position flatwise over the table and the garment thereon, a motor, folding members operable to fold portions of the garment relatively to the form and to other portions of the garment, motion transmitting means between the motor and the folding members and the form, a power system for the motor including an operator-operated control operable to control the flow of power to the motor, and a second control member operable by the initial lifting movement of the form with the folded garment thereon from a position flatwise on the table to effect de-energization of the motor, means for returning the folding mechanism and the form to their starting positions, when the motor is de-energized, a support for the motor, the form, the folding members and the motion transmitting means, said support being pivotally connected to the table, and the form being pivotally mounted on the support on an axis parallel to and spaced from the pivotal axis of the

support, and means tending to return the support to normal position, all whereby upward tilting force applied to the form when flatwise on the table and the motor is energized tilts the support about its pivot, and connections between the pivoted support and the second control member to operate it.

6. A garment folding machine including a table on which the garment is laid flatwise, a form mounted to shift into and out of a position flatwise over the table and the garment thereon, a motor, folding members operable to fold portions of the garment relatively to the form and to other portions of the garment, motion transmitting means between the motor and the folding members and the form, a power system for the motor including an operator-operated control operable to control the flow of power to the motor, and a second control member operable by the initial lifting movement of the form with the folded garment thereon from a position flatwise on the table to effect de-energization of the motor, means for returning the folding mechanism and the form to their starting positions, a support for the motor, the form, the folding members and the motion transmitting means, pivotally connected to the table, said motion transmitting means including a shaft extending parallel to and spaced from the axis of the support, the form being pivotally mounted on the shaft, a connection between the shaft and the form by which the form is moved on its pivot by the rotation of the shaft into and out of position flatwise on the table, whereby upward tilting force applied to the form when flatwise on the table and the motor is energized tilts the support about its pivot, and connections between the pivoted support and the control member to operate it.

7. A garment folding machine including a table on which the garment is laid flatwise, a form mounted to shift into and out of a position flatwise over the table and the garment thereon, a pressure-operated motor, folding members operable to fold portions of the garment relatively to the form and to other portions of the garment, motion transmitting means between the motor and the folding members and the form, a fluid pressure system for the motor including an operator-operated, self-returning combined intake and exhaust valve normally arranged with the intake closed and the exhaust open, and a second control member consisting of a normally closed, self-closing exhaust valve, means operable by the tilting of the form with the folded garment thereon from a position flatwise on the table to open the second control member, and means acting on the motion transmitting mechanism tending to return the form, the motor and the folding members to their starting positions.

8. A garment folding machine including a table on which the garment is laid flatwise, a form mounted to shift into and out of a position flatwise over the table and the garment thereon, a pressure-operated motor, folding members operable to fold portions of the garment relatively to the form and to other portions of the garment, motion transmitting means between the motor and the folding members and the form, a fluid pressure system for the motor including an operator-operated, a first control member including a self-returning combined intake and exhaust valve normally arranged with the intake closed and the exhaust open, and a second control member consisting of a normally closed, self-closing exhaust valve, means operable by the tilt-

ing of the form with the folded garment thereon from a position flatwise on the table to open the second control member, and means acting on the motion transmitting mechanism tending to return the form, the motor and the folding members to their starting positions, the last means including a pressure-operated motor acting in opposition to the former motor and being of less power than the same, and also being connected in the power system in multiple with the first control member.

9. A garment folding machine including a table on which the garment is arranged, a form operable to shift into and out of a position flatwise over the table and the garment thereon, two sets of folding mechanism, each including folding members, one set of folding members being normally in position to coact with the garment, when actuated, to fold the same, and the other set operator-operated and initially out of position to coact with the garment, and movable into such position by the movement of the form into a position flatwise over the table and the garment, actuating mechanism, and connections operated thereby for operating the form into a position flatwise over the table and operating the first set of folders, and operator-operated control means for the actuating mechanism.

10. A garment folding machine including a table on which the garment is arranged, a form operable to shift into and out of a position flatwise over the table and the garment thereon, two sets of folding mechanism including folding members, one set of folding members being normally in position to coact with the garment, when actuated, to fold the same, and the other set initially out of position to coact with the garment and movable into such position by the movement

of the form into a position over the table and the garment, actuating mechanism, and connections operated thereby for operating the form and first set of folding members, and control means for the actuating mechanism, the second set of folding members being manually operable, means tending to return them to their starting positions, releasable holding means operated by the control means for holding them in their folded positions, the control means including timer means for effecting first the operation of the form and the folding operation of the first set of folding members, and then the operation of the holding means for the operator-operated folding members and the return of the first set of folding members, the release of the holding members and the return of the form in the reverse order upon the release of the control means.

11. A garment folding machine including a table, on which the garment is arranged, a form mounted to shift into and out of a position flatwise over the table and the garment thereon, folding mechanism operable to fold a portion of the garment relatively to the form and the other portions, a pressure-operated motor for operating the folding mechanism to effect the folding, and a second pressure-operated motor for returning the folding mechanism to starting position, a power system for the motors, the second motor being of less strength than the first motor and being in constant open communication with the power system, an operator-operated control member in the power system for controlling the energization of the first motor, and a second control member operated by the initial movement of the form away from the table to effect the de-energization of the first motor.

HARRY G. COOPER.
